Inventor:

Edward S. Halsey.

UNITED STATES PATENT OFFICE.

EDWARD S. HALSEY, OF YONKERS, NEW YORK.

TEMPERATURE-REGULATING VALVE MECHANISM.

1,285,991.

Specification of Letters Patent. Patented Nov. 26, 1918.

Application filed October 30, 1916. Serial No. 128,550.

To all whom it may concern:

Be it known that I, EDWARD S. HALSEY, a citizen of the United States, residing at Yonkers, in the county of Westchester and State of New York, have invented certain new and useful Improvements in Temperature-Regulating Valve Mechanisms, described and set forth by the following specifications and claims.

10 This invention relates especially to the thermostatic control of steam flow or supply valves in the development of which I have employed the principle of operation disclosed by Patent Number, 1129433 of Julian Stratton, issued Feb. 23rd, 1915, in which a volatile liquid is dripped into a hot volatilizing chamber from whence it distils out into a cold chamber and from which its return to the hot chamber is controlled by 20 external thermostatic means.

The objects of my invention are to contrive means of incorporating this principle into a steam throttling valve so that by simple and efficient means the main throttle 25 valve will be internally actuated by the powerful expansion of the volatile liquid under the sensitive control of a primary external thermostat, of relatively small and sensitive proportion.

30 Referring to the accompanying drawings which illustrate my invention similar reference characters refer to similar parts throughout the several views in which Figure 1 is a side elevation in cross section 35 of an angle steam valve with thermostatic attachments. Fig. 2 is a horizontal cross-section through 2—2 of same. While Fig. 3 is a side elevation in cross section of a similar valve to that shown in Fig. 1.

40 Referring to Fig. 1, the angle body 1, includes an elastic metal expansion chamber, 2, which is attached to a hollow stud of bonnet, 12, through which it communicates to the condensing chamber, 3, by means of the 45 insulating tubular neck, 5, and the crescent channel, 9. In this case the primary expansion from vaporization of the dripping liquid occurs where the drops fall on the hot chamber walls in the passage-way to the 50 diaphragm section of the expansion chamber or space. The bottom of this condensing chamber which is spherical in form constitutes a catch basin for the condensing liquid 4. At the lowest central point is a 55 small opening, normally closed by the weighted needle valve, 6, the upper end of

which is guided by the bushing, 8. This needle valve may be raised and opened by a very slight raising pressure on the angle lever, 7, which is fulcrumed in the center of 60 a small thin flexible metal diaphragm, 17, which is soldered or otherwise secured over an aperture in the side of the condensing chamber. This lever or valve stem is clamped firmly on either side of the dia- 65 phragm by a pair of crown-faced nuts, 16, which permit it to rock practically free of friction and with hardly an appreciable distortion of the diaphragm with a very minute application of energy. In this figure the 70 thermostatic source of energy is indicated as being supplied by the bi-metal bar, 13, anchored at the lower end and pressing on the valve lever through the medium of an adjusting screw at the top end. This illus- 75 trates symbolically the application of any known type of primary thermostat which may be used in carrying out this invention.

In Fig. 3, the valve lever, 7, instead of being L shaped is left straight and its outer 80 end is shown as being connected with a distant actuating thermostat (which may be of any type desired) through the medium of the tensioned ligament, 15, passing over pulley, 18, or otherwise.

85 In this figure I have shown an accordion bellows expansion chamber instead of the double diaphragm expansion chamber shown in the first figure. To the bottom of the bellows is fixed a cone, 19, constituting a 90 throttle by closing, and seating on, the opposing port. I have also shown an additional communicating tube, 5', for the hot vapor to pass up through to the condensing chamber in addition to the central thermal insulating tube, 5, through which the liquid 95 drips into the hot chamber.

In order to make the whole device compact and of short stature and have the condenser rapid and efficient in action I cut 100 down the conducted heat between the hot valve body and the air cooled condensing chamber to a very large degree by employing connecting tubes, 5, of thin cross-section and made from thermal insulating metals, 105 or in other words having relatively high heat resistance as compared to that of the brass of which the valves are made, for instance, iron which has over twice the resistance of brass. I prefer however to use an 110 alloy of nickel steel high in nickel which has many times the resistance of iron or

brass, or alloys of nickel and copper, such as Monel, or conglomerate mixtures of iron, nickel, copper, etc., such as German silver, nichrome, etc.

5 While I have only shown two modifications of my invention, it is obvious that it may be made up and applied in numerous other forms and applications. For instance, instead of the rock lever and dia-
10 phragm, pressure diaphragms may be em-
ployed and instead of the mechanical ap-
plication of the power from the primary
thermostat, it may be communicated through
fluid pressure tubes, etc., etc.

15 I claim:

1. In a radiator supply valve, a body housing a throttle; a flexible expanding chamber in said body connected to said throttle; an intercommunicating air cooled
20 condensing chamber above said expanding chamber; a catch basin for said condensing chamber; a drip valve between said basin and said lower expanding chamber; an external primary actuating thermostat in
25 working engagement with said drip valve; and a relatively slender thermal insulating neck between said air cooled chamber and the heated body of said valve.
2. In a steam supply valve a body housing
30 a throttle; a flexible expanding chamber in said body connected to said throttle; an externally cool condensing chamber above said

expanding chamber; a catch basin for said condensing chamber; a drip valve between said basin and lower expanding chamber; an external primary actuating thermostat in
35 working engagement with said drip valve; and a thermal insulating neck between said externally cooled chamber and the heated body of said valve consisting of a relatively 40 poor conducting metal alloy.

3. In a thermostatic steam throttling valve a throttling device; a housing body therefor; a flexibly walled, normally dry, vaporizing, throttle actuating expansion 45 chamber incorporated in and heated by contact with said body and steam; a cooled, intercommunicating condensing chamber of higher elevation than the vaporizing portion of said expansion chamber; a liquid 50 catch basin to said condensing chamber; a drip valve from said basin controlling the flow of said liquid to said vaporizing expansion chamber; and a primary external thermostatic controlling device in working 55 engagement with said drip valve.

Having described my invention I hereunto set my hand in the presence of two witnesses this 12th day of September, 1916.

EDWARD S. HALSEY.
